UNITED STATES PATENT OFFICE.

ALBERT BALL AND THOMAS OFFICER, OF CLAREMONT, NEW HAMPSHIRE,
ASSIGNORS TO THE SULLIVAN MACHINERY COMPANY, OF SAME PLACE
AND CHICAGO, ILLINOIS.

ENGINE.

SPECIFICATION forming part of Letters Patent No. 661,685, dated November 13, 1900.

Application filed March 22, 1900, Serial No. 9,677. (No model.)

To all whom it may concern:

Be it known that we, ALBERT BALL and THOMAS OFFICER, residents of Claremont, in the county of Sullivan and State of New Hampshire, have invented a new and useful Improvement in Engines; and we do hereby declare the following to be a full, clear, and exact description thereof.

Our invention relates to direct-acting fluid-pressure engines—such, for example, as those employed for operating drills or other reciprocating tools; and it has for its object to provide a simple, inexpensive, and efficient means for so governing the speed of travel of the piston when the tool operated by it is doing no work as to avoid danger of injury to the engine and either injury or serious discomfort to the user. With this end in view we have devised means actuated by live fluid at approximately normal working pressure to control the speed of the main piston either by throttling the supply of live fluid to the cylinder of the engine at some point in its course to the main cylinder or by controlling the operation of the main valve, the distinguishing characteristic being the utilization of the governing fluid at approximately normal working pressure.

The fluid employed for operating the engine embodying our invention may be steam, air, or other gas under pressure; but for convenience of description we shall designate the operating fluid as air, that being the agent most commonly employed in engines of this character.

It is well known that compressed-air or steam engines employed for actuating drills in mining operations are more satisfactory in operation and are more economical in the use of the actuating fluid employed if some automatic means be employed for preventing the racing of the engine when the drill meets no obstruction to its forward movement. Such a means is set forth in Patent No. 603,358, granted to the Sullivan Machinery Company May 3, 1898, as assignee of Albert Ball, wherein an auxiliary valve is operated by the air compressed in front of the piston, so as to control the flow of live air to the cylinder. In Patents Nos. 615,234 and 615,236, granted to the Sullivan Machinery Company Decem-

ber 6, 1898, on applications filed by us, are set forth other means for regulating and governing the operation of the pistons of engines of the type to which our present invention pertains. Many of the features of construction shown in the accompanying drawings are fully set forth in the above-mentioned patents, and reference may be had thereto for a detailed description of parts not specifically described herein.

In the accompanying drawings, Figure 1 is a vertical longitudinal section of a direct-acting engine embodying one form of our invention. Fig. 2 is a plan view of the cylinder 65 of the engine with the air-chest and main governing-valve removed to show the ports. Fig. 3 is a view of the engine, partially in section and partially in end elevation, the air-chest and main valve being omitted. Fig. 4 70 is an end elevation of the main frame or casting, the end plate being removed. Figs. 5 and 6 are respectively a front and a side elevation of the reversing-valve. Fig. 7 is a view similar to Fig. 1, but embodying a modified arrangement of governing device. Fig. 8 is an end elevation of a portion of the main frame or casting shown in Fig. 7, the end plate being removed. Fig. 9 is a view, partially in end elevation and partially in section, of an engine embodying a modification of our invention. Fig. 10 is a side elevation of the rear end portion of the engine shown in Fig. 9. Fig. 11 is a view similar to Figs. 1 and 7, but embodying a modified form of 85 governing device.

Referring now particularly to Figs. 1 to 6, inclusive, the piston rod or stem 1, to the outer end of which is attached the drill or other tool to be operated, is reciprocated by a piston 2, operating in a cylinder 3 in the usual manner. The piston 2 is provided with a nut, with which engages a rifle-bar 4, having on its outer end a pinion 5, the bar and its pinion being given a rotary motion in the one 95 direction or the other as the piston is reciprocated by the fluid-pressure exerted against its respective ends. Live air is admitted to the air-chest 6 through a port 7, and its passage from the chest 6 to the main cylinder 3 and 100 from the cylinder to the main exhaust-port is controlled by the differential piston 8, this

piston being rigidly connected to the main valve 9, which directly controls the passage of air through the inlet ports or passages 10 and 11 at the rear end of the cylinder, the 5 inlet port or passage 12 at the front end of the cylinder, the exhaust ports or passages 13 and 14 at the rear end of the cylinder, and the exhaust ports or passages 15 and 16 at the front end of the cylinder. The main exhaust, with which the exhaust-ports from the front and rear ends of the cylinder are put in communication by means of the valve 9, is shown at 17.

In order to provide for the compression of 25 air in the front end of the cylinder after the piston passes the exhaust-port 15, and thus cushion the piston, we provide a check-valve 18, this valve being so located in the inlet-passage 12 that it will be easily raised from 20 its seat when the live air is admitted to the passage 12, but prevent any flow of air in the opposite direction.

The construction of the ports 10 and 11, whereby the piston is given a quick initial 25 movement, and the character of the port 20 in the valve 9, whereby the piston is caused to have a slow backward movement, are fully set forth and claimed in the patents hereinbefore referred to.

30 The space 21 behind the large end 8^a of the piston 8 is in communication with the chamber 22, formed at the rear end of the cylinder 3 by a cap-plate 23, through a passage 24 and a port 25, the latter being located 35 in an adjustable plate 26, the spring-arms 26^a for adjusting this plate and the function of said parts being fully set forth in the above-mentioned Ball and Officer patents.

40 A passage 27 supplies air at the normal working pressure from the air-chest 6 to the chamber 22, and this pressure is exerted in the space 21 until the reversing-valve 28 is moved a sufficient distance to cover the port 25, this movement of the reversing-valve being effected by the pinion 5, which meshes 45 with the rack 29 on the upper edge of the valve.

When the return stroke of the main piston is completed and the reversing-valve is correspondingly moved so as to cover the port 50 25, the groove 28^a in the valve 28 will bridge the ports 26^b and 26^c in the plate 26, and the air-pressure will be exhausted from the space 21 through the passage 21^a, the said ports and 55 groove, and the passage 21^b. The pressure in the space 21 will be sufficient to maintain the piston 8 in the position shown in Fig. 1 until the air is exhausted from said space, and when this action takes place the live air entering through 60 the port 7 will throw the piston, and with it the valve 9, so as to reverse the piston 2. It will be readily seen that, as shown in Fig. 1, the piston has reached the forward limit of its stroke and the parts are in position to admit air to the front end of the cylinder and 65 return the piston to its rear end.

In order to provide for a slow return move-

ment of the piston when the tool operated by it is doing no work, and therefore when it has made a forward stroke of greater length than 70 it would make if resistance were offered to its movement, we provide a passage 30, leading from the chamber 22 to the space behind a differential valve 31, the smaller end of which is movable into the live-air passage 12, 75 leading to the front end of the cylinder 3. When the reversing-valve 28 is carried to the position indicated in Fig. 3 by reason of this extreme forward movement of the piston the opening to the passage 30 is uncovered, and 80 live air is therefore admitted behind the differential valve 31; and the latter is thereby forced into the passage 12 a sufficient distance to throttle the inflowing air. After the reversing-valve 28 is moved a sufficient distance in its reverse direction to shut off communication with the passage 30 the compressed air behind the valve will leak out through a small vent-hole 31^a.

We employ a differential valve as a governing-valve, since it is intended to throttle the live air and is actuated by air at approximately the same pressure. The inner end of the valve 31 may be provided with a projecting pin 31^b, as indicated, the length of which 95 will be determined by the amount of throttling it is desired to effect by the valve, since this pin serves to limit the inward movement of the valve.

Referring now to Figs. 7 and 8, the several 100 parts in so far as they do not differ from the parts shown in the preceding figures will be designated by the same reference-numerals, and the description heretofore given of the same in connection with the other figures may 105 be therefore applied to the construction here illustrated. The only difference between the construction here illustrated and that shown in the preceding figure resides in the location of the governing-valve 32, this valve in the 110 present case being located in the passage 11, leading to the rear end of the cylinder 3, and therefore serving to control the live air introduced for the purpose of giving the piston its 115 forward stroke. The valve 32 is preferably 120 of the differential type and may be of the same construction as that employed in connection with the construction shown in Figs. 1 to 6. The passage 30^a, leading from the chamber 22 to the valve 32, is opened and closed by substantially the same means and in the same manner as the corresponding passage leading 125 to the valve 31 in the construction already described.

The construction shown in Figs. 9 and 10 130 is the same as that shown in the preceding figures and hereinbefore described except as regards the regulating means, and such means only will therefore be now described. Instead of locating the governing-valve in either 135 the live-air passage leading to the front end of the main cylinder or in that leading to its rear end we locate it in the exhaust-passage 21^a, leading from the cylinder or space 21 to

the reversing-valve 28. The governing-valve 32^a is preferably of the differential type and is operated by live air admitted behind the same through a passage 40, the inlet end of which is uncovered when the reversing-valve is in one of its extreme positions, as is indicated in Fig. 9.

In Fig. 11 we have shown a construction whereby the governing-valve throttles the live air before it reaches the chest 6. The construction shown in this figure is the same as that shown in Figs. 1 and 7 except that the governing-valves shown in those figures are omitted, and the passage 30^b from the chamber 22, through which the live air passes for operating the governing-valve, is of different length and location from the corresponding passages in the constructions already described. It will be understood, therefore, that the description heretofore given is applicable to the structure here shown and may be read in connection with this figure in so far as the construction is not modified in the manner to be now described. Adjacent to the inlet-port 7 we locate a cylinder 33 and in this cylinder place a differential valve 34, the smaller end 35 of which projects into the passage 36, leading from the inlet-port 7 to the chest 6. A small vent-opening 37 is provided at the front end of the cylinder 33, and a similar vent-opening 38 is provided at the rear end. In order to limit the inward movement of the valve 34, we may employ a stop 39 in the form of a set-screw, this screw being moved in or out in accordance with the amount of throttling desired. Obviously a different form of stop might be employed, or the end of the part 35 might be partially cut away, so that it would be impossible to entirely close the inlet-passage. When air is admitted through the passage 30^b into the cylinder 33 behind the valve 34, the latter will obviously be projected so as to partially close the inlet-passage, and thus reduce the speed of the piston. With this arrangement it is obviously possible to so apply the throttling action that the retarding of the piston may be effected either in its rearward or in its forward movement, as may be desired, or the arrangement may be such that the piston will be retarded in both its forward and rearward movements.

It will be readily seen that each of the modifications shown and described embodies means for governing the movement of the piston when its speed tends to increase by reason of the fact that the tool operated by it is doing no work. It will also be seen that in each case the increased length of travel of the piston causes the reversing-valve to uncover a port and passage leading from a chamber containing air at approximately the pressure employed in operating the piston and that this air is utilized to so actuate a governing-valve as to throttle the air supplied to the main cylinder for operating its piston.

The form and location of the parts utilized in practicing our invention may obviously be varied from what is specifically shown and described, and we therefore desire it to be understood that our invention is not limited in these respects except in so far as limitations are specifically embodied in the claims.

What we claim as our invention, and desire to secure by Letters Patent, is—

1. In a direct-acting, fluid-pressure engine, the combination with a cylinder provided with inlet and exhaust ports, of a main valve for controlling the same, a piston working in said cylinder and governing means actuated by fluid at approximately normal working pressure to control the movement of the piston when it tends to exceed its normal speed.

2. In a direct-acting fluid-pressure engine, the combination with a cylinder provided with inlet and exhaust ports, of a main valve for controlling the same, a piston working in said cylinder and governing means actuated by fluid at approximately normal working pressure to throttle the fluid supplied to the cylinder when the piston exceeds its normal stroke.

3. In a direct-acting, fluid-pressure engine, the combination with a cylinder provided with inlet and exhaust ports, of a main valve for controlling the same, a piston working in said cylinder, a differential valve for throttling the supply of fluid to the cylinder and means for supplying actuating fluid at approximately normal working pressure to said valve when the piston exceeds its normal stroke.

4. In a direct-acting, fluid-pressure engine, the combination with a cylinder provided with inlet and exhaust ports, of a main valve for controlling the same, a piston working in said cylinder, a governing-valve for throttling the live fluid supplied to said cylinder and means for applying live fluid at approximately normal working pressure to said governing-valve to positively actuate the same when the piston exceeds its normal stroke.

5. In a direct-acting, fluid-pressure engine, the combination with a cylinder provided with inlet and exhaust ports, of a main valve for controlling the same, a piston working in said cylinder, a governing-valve for throttling the live fluid supplied to said cylinder, a chamber in open communication with the main air-chest and containing a reversing-valve, and a passage leading from said chamber to the governing-valve chamber, said passage being uncovered by the reversing-valve when the piston exceeds its normal stroke.

In testimony whereof we, the said ALBERT BALL and THOMAS OFFICER, have hereunto set our hands.

ALBERT BALL.
THOMAS OFFICER.
